SNUBBED TRUCK

John J. Kowalik, Chicago, Ill., assignor to American Steel Foundries, Chicago, Ill., a corporation of New Jersey

Application October 8, 1948, Serial No. 53,530

16 Claims. (Cl. 105—197)

1

This invention relates to railway car trucks and more particularly to a novel truck incorporating friction means for snubbing oscillations of the truck bolster on its supporting springs.

A general object of the invention is to provide friction means of novel form cooperable with the truck bolster and the side frame to control various relative movements therebetween.

A more specific object of the invention is to design a truck comprising a friction element within each column of the side frame, each element engaging the bolster in such manner as to exert a pulling force on the bolster toward the related column, thereby effectively restraining lateral movements of the bolster, each element also frictionally engaging the related column for slideable movement therealong to control vertical bolster oscillations.

A further object of the invention is to devise a truck of simple, rugged form which is easy to assemble and disassemble.

The invention comprehends a friction element of novel form comprising spaced shoe and wedge portions with facing friction surfaces converging toward a spring seat member interconnecting said portions.

A different object of the invention is to provide friction means which develop variable friction to snub vertical bolster oscillations.

These and other objects of the invention will become more apparent from the specification and the drawings, wherein:

Figure 1 is a fragmentary side elevation, partly in section, of a car truck embodying the invention, the section being taken substantially on line 1—1 of Figure 2;

Figure 2 is a fragmentary view partly in section on line 2—2 of Figure 1;

Figure 3 is a fragmentary sectional view taken on line 3—3 of Figure 1; and

Figures 4 and 5 illustrate a modification of the invention, Figures 4 and 5 being sectional views corresponding to the right half of Figures 1 and 2, respectively.

Describing the invention in detail and referring first to the embodiment illustrated in Figures 1 to 3, inclusive, the car truck comprises a truss-type side frame generally indicated 2, including top and bottom or compression and tension members 4 and 6 and spaced upright columns or guide portions 8, 8 defining a bolster opening 10.

The tension member below the bolster opening 10 comprises a top chord 12 with upstanding inboard and outboard flanges 14 and 16 defining

2

with the top chord 12 a seat 18 confining a plurality of coil truck springs 20, 20 seated at their lower ends as at 22 on said seat 18 and at their upper ends as at 24 against the bottom wall 26 of the box-section bolster 28 and affording a support therefor. The springs 20, 20 are positioned on the seat 18 by means of spaced upstanding lugs 30, 30 on chord 12 of the tension member, and at their upper ends by spaced depending lugs 32, 32 on the bottom wall of the bolster.

The bolster 28 in addition to the bottom wall 26 comprises a top wall 34 spaced vertically from said bottom wall, said top wall 34 being connected at its lateral edges to the lateral edges of the bottom wall by substantially vertical side walls 36, 36. The top and bottom walls are additionally connected by an intermediate substantially vertical center rib or web 38 extending longitudinally of the bolster.

Inboard and outboard guide lugs 40 and 42 are provided on the external side of each side wall and embrace the associated column therebetween for interlocking the bolster with the frame. It will be observed from a consideration of Figure 1 that the outboard lugs 42, 42 are of a depth less than that of the widened lower portion 43 (Figure 1) of the bolster opening 10 to accommodate ready insertion and removal of the bolster in the assembly and disassembly of the bolster with respect to the side frame, as will be readily understood by those skilled in the art.

The bolster is provided with a pocket 44 (Figure 1) at each side thereof defined in part by the top and bottom bolster walls and the center rib, each pocket receiving a portion of a friction member 46 therein, the details of which may be seen from a consideration of Figures 1 to 3, inclusive.

The friction member 46 comprises a substantially horizontal wall or spring seat member 48 providing a spring seat 50 on its underside affording a bearing for the upper end of a generally vertical auxiliary or actuating coil spring 52 extending through a cored out opening 53 in the bottom bolster wall 26 adjacent the associated column 8 and seating at its lower end on seat 18 of the tension member. The inner end of the friction member comprises a wedge portion including a diagonal wall 54 and an upright wall 56. Wall 54 is connected at its lower end to the top surface of the horizontal wall 48 intermediate the ends thereof and extends toward the one or inner end of the horizontal wall 55. 48 which is disposed within the associated bolster

pocket 44, and the upright end wall 56 is connected at its lower extremity to the said inner end of said horizontal wall and merges at its upper end with the upper extremity of said diagonal wall. The forward extremity or other end of the horizontal wall 48 is necked down to fit into a vertical slot 58 defined between the inboard and outboard portions 60 and 62 of the associated column 8. A shoe portion is formed on the outer extremity of wall 48, said shoe portion comprising a V-shaped substantially vertical wall 64 connected at its apex 66 adjacent its lower end to the necked down portion of the horizontal wall 48. Wall 64 presents substantially vertical inboard and outboard friction surfaces 68 and 70 converging toward and facing the diagonal wall 54 of the wedge portion of the friction member. Substantially horizontal vertically spaced webs or gussets 72, 72 extend between and merge with the angularly related portions of the V-shaped wall 64 reinforcing the same.

The connection between the wall 64 and the horizontal wall 48 is strengthened by a substantially vertical wall 74 extending longitudinally of the friction member through said slot 58 in the associated column and connected at its lower end to the top side of said horizontal wall 48 and at its lateral edges to the V-shaped wall 64 at its apex 66 and to the upper or external side of said diagonal wall 54 in an area intermediate the lateral edges thereof.

The wall 54 is thus divided into inboard and outboard portions providing upwardly sloping coplanar wedge surfaces 76 and 78 facing the shoe portion of the friction member.

The bolster is provided at each side thereof with a pair of inboard and outboard diagonal walls or ledges 80 and 82 merging at their lower ends with the lower edge of the associated side wall of the bolster and at their upper ends with the inner or underside of the top wall of the bolster. As best seen in Figures 1 and 2, the ledges 80, 82 of each pair present slightly curved or crowned coplanar wedge surfaces 84 and 86, respectively, sloping upwardly inwardly of the bolster, said wedge surfaces facing downwardly into the associated pocket 44 away from the adjacent column 8. It will be noted that the wedge surfaces on one pair of ledges face the wedge surfaces on the other pair and the surfaces on respective pairs lie in planes converging inwardly of the bolster toward a vertical plane at the center line of the bolster, and that the ledges 80 and 82 of each pair are spaced longitudinally of the bolster and are disposed respectively inboard and outboard of wall 74 of the associated friction member. The ledges of each pair define a vertically elongated space therebetween in alignment transversely of the bolster with a vertical slot 88 in the associated bolster side wall and with said slot 88 accommodating the vertical wall 74 of the associated shoe within the bolster. The lower ends of ledges 80 and 82 are spaced from wall 48 and the adjacent portions of the associated bolster side wall are cored away to afford vertical clearance for the horizontal wall 48 of the associated friction member as it is moved inwardly of the bolster in operation, as hereinafter described. For the same purpose, the interconnected portions of the ledges 80 and 82 above wall 74 of the associated friction member are also vertically spaced from the upper edge of wall 74.

The wedge surfaces 84 and 86 on the associated ledges engage the surfaces 76 and 78 respectively

on the diagonal wall of the associated friction member to cause movement of the friction member inwardly of the bolster in response to the pressure exerted by the associated actuating spring.

The shoe portion of the friction member is received within the associated column 8, as best seen in Figure 2, and engages the inboard and outboard friction plates or panels 94 and 96 on surfaces 100 and 102 thereon, respectively; said panel surfaces 100 and 102 face away from the bolster, whereas surfaces 68 and 70 on wall 64 of the shoe portion face the bolster. The surfaces 68, 100 and 70, 102 are generally vertical and converge toward the bolster opening 10.

The inboard and outboard panels 94 and 96 are disposed respectively on adjacent sides of portions 60 and 62 of the related column 8 and are connected to angularly related walls 104 and 106 of respective portions as by welding at 108, 108. The walls 104, 104 of respective portions define one side of the bolster opening and are aligned transversely of the side frame and spaced apart to define the aforementioned vertical slot 58 therebetween, and the walls 106, 106 of respective portions lie in generally parallel vertical planes extending longitudinally of the frame. Each wall 106 is provided on its inner side with a boss 110 affording a complementary seat for the associated friction panel.

In operation, the friction members are actuated by the bolster and associated auxiliary springs and are constantly urged inwardly of the bolster through the action of the cooperating wedge surfaces 76, 84 and 78, 86 on the wedge portions of the respective shoes and related ledges 80 and 82, the auxiliary springs being under compression between respective friction members and the tension member spring seat. Thus the faces 68, 100 and 70, 102 on the shoe portion and column panels are caused to engage. As the bolster descends, the friction members move downwardly within the column, and further compress the respective auxiliary springs, whereby developing greater friction on the descent of the bolster between the friction members and respective columns than on the ascent.

To disassemble the truck for quick-wheel change, the bolster is elevated to relieve the compression on the springs. The truck springs and auxiliary springs are removed, allowing the friction members to drop to the lower end of the columns. The friction members are removed from the columns into the bolster opening through the lower portions 112 of the vertical column slots 58.

The friction members may also be removed through the adjacent side frame window 114. As shown in Figure 1, the lower portion 112 of the slots 58 are of a depth slightly greater than the height of the shoe or wedge portions of respective friction members and, as shown in Figure 3, are widened transversely of the side frame by coring away adjacent portions of webs 104, 104 of the inboard and outboard portions 60 and 62 of each column to a width slightly greater than the width of the shoe or wedge portion of the friction member. After the friction members are removed, the bolster is lowered to the widened portion of the bolster opening and withdrawn in usual manner. To assemble, the procedure is reversed.

A modification of the invention is illustrated in Figures 4 and 5 wherein parts corresponding to those of Figures 1 to 3 are identified by corresponding numerals. The bolster as shown in Figures 4 and 5 is provided with a plurality of spaced

vertical ribs 150 extending longitudinally of the bolster and interconnecting the top and bottom walls 34 and 26 thereof. In lieu of the spaced inboard and outboard ledges shown in Figures 1 to 3, the bolster in Figures 4 and 5 is provided with a single ledge 152 at each side thereof, each ledge providing a wedge surface 154 sloping upwardly inwardly of the bolster and lying in planes converging toward the vertical plane passing through the longitudinal center line of the bolster. The vertical wall 74 shown in the friction members described in the previous embodiment has been eliminated; however, the connection between the wedge and shoe portion of the friction member is strengthened by increasing thickness of wall 48 as at 156.

It will be noted that in both of these embodiments, generous areas of engagement between the column and friction member and between the bolster and the friction member are provided, thus reducing wear. Various movements of the bolster are effectively controlled by the friction means which effect a pulling action in opposite directions on opposite sides of the bolster, and also afford frictional control over vertical and longitudinal bolster movements.

In each embodiment the friction member and auxiliary springs are shown as supporting the bolster; however, it will be understood that the friction assemblies could be inverted by inverting the bolster wedge surfaces so that they face upwardly and by inverting the friction members and compressing the auxiliary springs between the friction members and the compression members.

The spring 52 could also be arranged to act between the bolster and the friction members so as to obtain constant friction between the friction members and the columns, as will be readily understood by those skilled in the art.

I claim:

1. A side frame having a bolster opening, a column at each side of said opening, each column comprising spaced inboard and outboard portions defining a substantially vertical slot therebetween open to said bolster opening, and a friction surface on each portion facing toward the adjacent end of the frame, each slot having a section at one of its extremities widened transversely of the frame and spaced vertically from the related surfaces and open thereto and to said bolster opening for accommodating assembly and disassembly of associated friction means with respect to the related column between the surfaces thereof through said opening.

2. In a railway car truck, a side frame comprising spaced columns, a bolster spring-supported from said frame between said columns, friction means at respective sides of said bolster, each comprising an element having a portion within the adjacent column frictionally engaging the same, and a portion pocketed in the adjacent side of the bolster, wedge means in the bolster extending between said last-named portion and the adjacent column, and spring means cooperating with said element for urging the same against said wedge means and moving the same along said wedge means to draw said first-named portion against the adjacent column.

3. In a railway car truck, a side frame member with spaced columns, a bolster member spring-supported from said frame member between said columns, friction elements at respective sides of said bolster member, each element comprising friction surfaces facing toward the bolster mem-

ber and engaging surfaces on the associated column facing away from the bolster member, wedge means on each element facing the friction surfaces thereon and in wedge engagement with the bolster member, and spring means reacting against respective elements and one of said members.

4. In a railway car truck, a frame member with spaced columns, a bolster member spring-supported from the frame member between said columns, a friction element at each side of the bolster member cooperable therewith and with the adjacent column for controlling relative movements between said members, resilient means reacting against each element and one of said members for urging the same into cooperation with said members, each element having wedge and friction surfaces facing each other and engaging said bolster member and associated column, respectively.

5. In a railway car truck, a side frame member having a bolster opening, a bolster member within said opening spring-supported from said frame member, a friction element partially received within each of said members and engaging said frame along generally vertical surfaces converging toward said bolster and engaging said bolster along wedge means on the bolster facing the vertical plane passing through the longitudinal centerline of the bolster, and means for urging said element into said engagement with said side frame and said bolster wedge means.

6. In a railway car truck, a side frame having a bolster opening, a column at one side of the opening with spaced inboard and outboard portions, friction surfaces on the adjacent sides of said portions converging toward said opening, a friction member between said portions engaging said surfaces and having an extension within said opening, spring means reacting between said member and said frame, and a bolster within said opening seated on said extension and having a wedging action therewith.

7. In a railway car truck, a side frame having a column, a bolster spring-supported from the frame adjacent one side of said column, an element in frictional engagement with the opposite side of the column, engaging wedge surfaces on said element and bolster arranged to slide said element toward the bolster for urging said element into engagement with said opposite side of the column, and spring means reacting against said element and said frame for urging said element into said engagement with the bolster and column.

8. In a railway car truck, a supporting member, a supported member, resilient means carried on said supporting member below said supported member, a friction element on said resilient means comprising angularly arranged facing surfaces on a side thereof remote from said resilient means and converging toward the same, said element receiving a portion of each member between said surfaces and engaging the same along complementary areas, said resilient means urging said element into said engagements.

9. In a railway car truck, a side frame having a bolster opening, a friction surface on said frame at one side of the opening facing toward the adjacent end of the frame, and friction spring actuated means engaging said surface and having a wedging action with the bolster, said wedging action being arranged to constantly urge said friction means inwardly of the bolster to thus

maintain said friction means in engagement with said surface.

10. In a railway car truck, a side frame comprising spaced columns having apertures therethrough, a bolster spring-supported from said frame between said columns, a friction member disposed through the aperture provided in each column and in engagement with the side of the column remote from the bolster along diverging surfaces thereon facing away from said bolster, resilient means reacting between said frame and said member for urging the member against the bolster, and a wedge surface on said member in wedge engagement with said bolster.

11. In a railway car truck, a side frame comprising spaced columns, each provided with an aperture therethrough, a bolster between said columns spring-supported from the frame, a friction member disposed through the aperture in each column and in engagement with the side of the column remote from the bolster along a pair of surfaces on the column both facing away from the bolster and in wedge engagement with the bolster, and resilient means compressed between said member and said frame for urging said member into said engagements.

12. In a railway car truck, a side frame member, a bolster member spring-supported therefrom, a friction element having spaced portions receiving a portion of each member therebetween and in wedge engagement therewith, and resilient means reacting between said element and one of said members for urging said element into said engagement.

13. In a vehicle, a supporting member, a supported member, and friction means comprising friction elements, each having a wedge surface and angularly related friction surfaces, said wedge surface facing said friction surfaces, each element having a wedging action with the supported member along said wedge surface and frictional engagement with the supporting member along said friction surfaces.

14. A friction member for a railway car truck having two angularly related vertical friction surfaces and having a third surface diagonally positioned with respect to both of said first-mentioned surfaces and facing the same.

15. In a railway car truck, a side frame with spaced columns, each provided with an aperture therethrough, a bolster resiliently supported from the frame between said columns, wedge surfaces on said bolster adjacent respective columns, a friction member at each side of the bolster comprising a wedge portion in wedge engagement with the adjacent surface and a shoe portion in frictional engagement with a side of the column facing away from the bolster, and a wall portion extending through the column aperture and connected to said wedge portion and shoe portion, said wall portion being subjected to a tensile stress, and spring means cooperating with said element urging the same into said wedge and frictional engagements.

16. In a railway car truck, a side frame with spaced columns, one having an aperture therethrough, a bolster spring-supported from the side frame, and a friction member engaging a surface on the column facing away from the bolster, said friction member comprising a wedge portion in wedge engagement with the bolster and a shoe portion in frictional engagement with said column surface and a wall portion extending through the column aperture and connected to said wedge and shoe portions, said wall portion being stressed in tension.

JOHN J. KOWALIK.
